UNITED STATES PATENT OFFICE.

JOSEF BRÜCKNER AND FRANZ HAMBERGER, OF BROOKLYN, NEW YORK.

AUTOMATIC CONTROL FOR VALVES

1,241,191.

Specification of Letters Patent. Patented Sept. 25, 1917.

Application filed March 9, 1916. Serial No. 83,067.

To all whom it may concern:

Be it known that we, JOSEF BRÜCKNER, a subject of the Emperor of Austria, and resident of Brooklyn, in the county of Kings and 5 State of New York, and FRANZ HAMBERGER, a subject of the Emperor of Austria, and resident of Brooklyn, in the county of Kings and State of New York, have invented certain new and useful Improvements in Automatic Controls for Valves, of which the following is a specification.

This invention relates to improvements in thermostatic controlling devices, and particularly to devices used in connection with 15 internal combustion motors, such as are commonly employed in connection with self-propelled vehicles.

One of the principal objects of the invention is to provide means which automatically drain the cooling tank should the temperature approach nearly to the freezing point.

Another object is to provide means which can be reset by a single operation, the device 20 being simple in construction, effective in operation, and occupying a minimum space only.

These and other objects are attained by the novel construction and combination of 25 parts hereafter described and shown in the annexed drawings, forming a material part of this specification, and in which:

Figure 1 is a vertical sectional view of the thermostatic device, taken on line 1—1 of Fig. 2.

Fig. 2 is a partial plan and sectional view, the section being taken on lines 2—2 of Fig. 1.

Fig. 3 is a partial side elevation and sectional view, showing a slight modified form of construction.

Fig. 4 is a top plan view of the same.

Fig. 5 is a side elevation of the controlling means, parts being shown by broken lines 45 in an open position.

Fig. 6 is another side elevation taken in a plane transverse to Fig. 5.

Fig. 7 is a sectional view taken on line 7—7 of Fig. 5, and

Fig. 8 is a diagrammatic view illustrating the wiring and relative location of the parts employed.

In carrying out the purpose of the invention, use has been made of the expansion or 55 contraction of certain materials or substances to actuate an electrically operated

valve controlling device, as will hereinafter become more fully apparent.

In Figs. 1 and 2 the device is shown to consist of a tube 10, coiled in a spiral helix, 60 while in Figs. 3 and 4, the helix is flattened to a certain extent.

In either case, the lower element of the coil is directly connected with a vessel 11, of considerable area, which, together with the 65 coils, is filled with a substance, as mercury, alcohol, or ether, which will expand or contract under changes in temperature of the surrounding atmosphere.

The upper end of the coil 10 is connected 70 with a hollow sleeve element 15, supported by screws or the like 16, the same passing through a cylindrical sleeve 18, which forms a continuation for the lower casing element 19, mounted on the base plate 20, attached 75 to any convenient part of the mechanism to which the engine is engaged.

The bore of the sleeve 15 contains a piston 22, normally resting upon the surface of the substance contained in the coil, so as 80 to be raised or lowered through its contraction or expansion.

To the piston 22 is engaged a stem 23 carrying a contactor head 24, held in place by the nut as shown.

The rod 23 passes upward through an insulating cup 26, one portion of which surrounds the upper end of the sleeve 15, and is held in place by a metallic cover 28, through the enlarged central opening of 90 which the rod 23 freely operates.

Connected with the cover 28, is a wire 30, leading to a terminal 31, insulated by the bushing 32, secured in the casing cover 35, in which at another point, is secured another 95 terminal, the wire 36 of which leads to the control device, as does also the wire 37, from the terminal 31.

The control device is secured to the tank drain pipe 40 by means of a clip-band 41, 100 and consists of the valve 42, to the stem 43 of which is connected a lever 45 normally actuated in one direction by the coil spring 44, surrounding the valve stem 43, and adapted to be held so that the valve is in an open position by the catch 46, affixed to the armature 47, the armature being guided by rods 48, and held normally downward under pressure of the coil springs 49.

The upper end of these rods is rigidly 110 engaged with the plate 50, the springs 49 also abutting against it, so as to press the

armature downward; the plate 50 is secured directly by the clip 41 to the pipe and has depending centrally between the rods 48, a magnet 52 which when energized serves to 5 retract the armature, and release the lever from engagement with the catch 46.

Thus when the material in the coils 10, contracts to such an extent as to permit the contact head 24 to make contact with the 10 cover 28, the electric circuit is closed, the cover 28 being directly connected by the wire 30 with one terminal wire 37, while the sleeve 15, through which the rod 23 operates, is in electric circuit with the other wire 36, 15 through the cover 35, casing 18 and screws 16.

The circuit can be traced from the battery 75 to the thermostatic control at the binding screw 31. From this control switch the circuit is traced through wire 36, through the 20 elements 53 and 54 of the release switch, kept normally closed by the head 60 of the resetting rod 57.

From the element 54 the current passes through the electromagnet 52, thence through 25 the wire 62, terminal 63 to terminal 64, wire 65 and back to the battery 75.

The valve is operated automatically through lowering of the temperature of the atmosphere to such a degree as to close the 30 thermostatic control switch, thus energizing the magnet, causing the armature to rise and release the valve lever 45; this lever when freed from the catch 46 is moved downward by action of the spring 44 and caused to engage 35 with the toe 56 formed on the rod 57 held vertically in supports and maintained in a normally raised position by the spring 58; when the rod is lowered the head 60 is withdrawn from the elements 53 and 54 so that the electric circuit is broken, and so 40 remains until the lever 45 be raised and reset in engagement with the catch 46.

From the foregoing, it will be seen that an efficient and simple means for drawing

water from the cooling system is disclosed, 45 and that the same will become operative by lowering of the temperature to such point as may render the engine inoperative.

Having thus described our invention, what we claim as new and desire to secure by Letters Patent, is:—

1. In a valve control system, the combination with a normally open gate valve, an operating lever engaged therewith, a magnet, an armature operated by said magnet having 55 a catch engageable with said lever, a source of electric energy connected with said magnet, a make and break switch in the electric connections, means combined with said switch operable by the action of said lever 60 when released, whereby the circuit is broken, releasing the armature, a thermostatic coil containing an expansible medium, a plunger operated thereby, means combined with said plunger for closing the electric circuit 65 whereby said magnet is energized, and a manually operated resetting means for said lever.

2. In a valve control system, a helically coiled tube and an expansible medium contained in said tube, of a sleeve engaged with the upper convolution of said coil, means for holding said sleeve rigidly, a piston operative in said sleeve, an insulated cap carried by said sleeve, a source of electric energy, one wire from which is connected with said cap, and the other wire with said sleeve, a contacting element carried by said piston, whereby as it descends, the electric circuit is closed, a gate valve, and means being operated through said electric current.

Signed at New York, in the county of New York and State of New York, this 19th day of February, 1916.

JOSÉF BRÜCKNER.
FRANZ HAMBERGER.
